CHRISTOPHER BRUNSCHWILER, OF NEW YORK, N. Y.

Letters Patent No. 91,905, dated June 29, 1869.

IMPROVEMENT IN COMMERCIAL ACCOUNT-INDICATOR.

The Schedule referred to in these Letters Patent and making part of the same.

To all whom it may concern:

Be it known that I, CHRISTOPHER BRUNSCHWILER, of the city, county, and State of New York, have invented a new and improved Stock and Balance-Indicator; and I do hereby declare that the following is a full, clear, and exact description thereof, which will enable others skilled in the art to make and use the same, reference being had to the accompanying drawings, forming part of this specification.

This invention relates to a new and improved method of showing or indicating the state of the account of those dealing in gold and stocks, with brokers and bankers, and for all operations of a similar nature; and

It consists in an apparatus composed of a skeleton tablet and changeable blocks, containing names, words, letters, and figures, whereby a quick, reliable, and legible exhibit is made by the book-keeper as often as may be required.

In the accompanying plate of drawings—

Figure 1 is a face view of the indicator.

Figure 2 is a cross-section, through the line x of fig. 1.

Similar letters of reference indicate corresponding parts.

Practical accountants, cashiers, and tellers of banking-houses, stock-operators, mercantile houses, and factories, have daily experienced the necessity of some new and practical device by which debit or credit balances, and the number of shares of stock (either "short" or on hand,) can be readily and concisely ascertained, without resorting to ledgers, balance-books, or other books of entry, besides the respective indexes thereto.

These operations, when performed by the most skilful accountants, always occasion too much loss of time and labor, especially in banking and stock-operations, where balances should be so arranged as to be seen at a glance. Successful operations in gold, stocks, and other speculating property, frequently depend on a single moment of time, especially in an era of violent fluctuations.

In carrying out my invention, I provide small blocks, together with a systematic arrangement of printed numbers, names, and words thereon, which are made to fit into grooves in a skeleton tablet, so as to be readily changed, according as the respective accounts change.

A represents the tablet or indicator, which is made of wood or other suitable material, and of any desired size.

B represents the grooves in which the removable blocks C are placed, as seen in the drawing.

D represents partitions, by which the grooves are divided into spaces for designating the name of the firm, the different kinds of stock or property operated in, and the balance at the right hand, which shows the condition of the account.

The blocks which indicate the name of the firm and also the balance, are made with grooves, to receive

slips of paper containing the name and figures, as seen distinctly at e, fig. 2.

Instead of grooved blocks for receiving slips of paper, with printed figures indicating the balances, type may be used, or a block for each letter, should it be desired to do so, and also for the other figures and letters in the indicator; but generally, it will be found more convenient to have the name of the firm, and the different kinds of stock or property, printed on slips of paper or on blocks, as represented.

It will be seen that the Bank of New York is dealing in gold, in Government five-twenty bonds, and in Erie, Rock Island, and Reading railroad stocks.

It will be noticed that the amount of gold is "10 M," or ten thousand dollars; the "five-twenties," nine thousand dollars; "Erie," five hundred shares; "Rock Island," one hundred shares; and "Reading," three hundred shares.

The red figures indicate that the Bank of New York is "short" in gold, five-twenties, Erie, and Reading, and has one hundred shares of Rock Island on hand.

The separate values of each are estimated, and the balance struck and indicated at the right hand, with balance of any amount of cash which may have been deposited.

This, we will suppose, indicates the state of the account with the Bank of New York on any morning, the blocks and figures having been correctly arranged by the book-keeper. Any changes which occur during the day, in stock or other transactions, may be duly noted by corresponding changes in the blocks or figures, so that the exact state of the account may be seen at once.

The indicator may be covered with glass, and kept in a drawer under lock and key, if desired.

In this example of my invention, I have shown a space beneath the indicator-face, for keeping a variety of blocks or letters, ready for use in making changes in the various accounts.

Having thus described my invention,
I claim as new, and desire to secure by Letters Patent—

The indicating-frame or tablet A, provided with receiving-grooves B, and with appropriate columns for the names of mercantile firms or correspondents, for the several kinds of property or values involved, and for balances, separated by the partitions D, in combination with replaceable blocks bearing names, words, letters, and figures, to give the indications or accounts desired, the whole being arranged in the manner and for the purpose herein shown and described.

The above specification of my invention signed by me, this 27th day of November, 1868.

CH. BRUNSCHWILER.
